CLAIM

The ornamental design for a horseshoe, as shown and described.

DESCRIPTION

FIG. 1 is a top, rear, left perspective view of a horseshoe, showing my new design.

FIG. 2 is a bottom, front, right perspective view thereof.

FIG. 3 is a top plan view thereof.

FIG. 4 is a front elevation view thereof.

FIG. 5 is a bottom plan view thereof.

FIG. 6 is a left side elevation view thereof, the right side elevation view being a mirror- image thereof.

FIG. 7 is a rear elevation view thereof; and,

FIG. 8 is a top, rear perspective view thereof.

In the drawings, the equal-length broken lines depict unclaimed portions of the horseshoe that form no part of the claimed design. The dash-dot-dash broken lines define the boundaries of the claim. All broken lines form no part of the claimed design.
